UNITED STATES PATENT OFFICE.

JAMES H. JOHNSON, OF NEWARK, NEW JERSEY, ASSIGNOR TO JOHNSON MANUFACTURING COMPANY, OF SAME PLACE.

DESIGN FOR AN INKSTAND-BASE.

Specification forming part of Design No. **8,011**, dated January 19, 1875; application filed December 1, 1874.
[Term of Patent 3½ years.]

To all whom it may concern:

Be it known that I, JAMES H. JOHNSON, of Newark, in the county of Essex and State of New Jersey, have invented a Design for Inkstands, of which the following is a specification:

My invention consists in certain ornamental figures wrought in or attached to an inkstand-base, and in the duplication of parts of this design, as may be required.

On the form of base shown, in Figure 1 of the photographic representations sent, is wrought the specific order of ornamental forms illustrated; and on the corners E¹ are attached the kneeling images B with wings. In the recess in front of the bottle E is the figure of a human face, D, and on the top of the cover of the bottle is wrought the monogram of the "Johnson Manufacturing Company."

This design may be duplicated in part by producing the front, embracing the corners E¹, images B, and recess and figure D on the back

of the bottle, as shown in Fig. 2; also, as shown in Fig. 3, wherein the parts of two stands, embracing of each one image, B, one figure D, and bottle E are joined together, and in the center, between the bottles, the bevels, and one bar of the base and ornamentation, are left out, and only one bar is retained, and the point f, between the figures D, has on it an ornamental standard, K, with a divided top, in the place of the images.

I claim—

1. In the design for an inkstand-base, the form of ornamentation around the sides, as shown.
2. In a design for inkstand-base, the form of the human head, D, as shown.
3. The form of the kneeling images B, having wings, as shown.

JAS. H. JOHNSON.
